A. E. LOOKHOLDER

COMBINED LIQUID FILLING AND DISPENSING ATTACHMENT

Filed Nov. 3, 1922

Inventor:
G. E. Bobbitt
By Dummer & Dummer 1977

UNITED STATES PATENT OFFICE.

ALEX E. LOOKHOLDER, OF OAK PARK, ILLINOIS, ASSIGNOR OF ONE-THIRD TO EVA M. HEBSTROM, ONE-THIRD TO ALICE E. LOOKHOLDER, AND ONE-THIRD TO FRANCES WEXELMAN, ALL OF OAK PARK, ILLINOIS.

COMBINED LIQUID FILLING AND DISPENSING ATTACHMENT.

Application filed November 3, 1922. Serial No. 598,762.

To all whom it may concern:

Be it known that I, ALEX E. LOOKHOLDER, a citizen of the United States of America, and a resident of Oak Park, county of Cook, 5 and State of Illinois, have invented a new and useful Improvement in Combined Liquid Filling and Dispensing Attachments, of which the following is a specification.

The main objects of this invention are to 10 provide an improved combined filling and dispensing attachment for use with liquid containers where the liquid is to be dispensed by means of air pressure; to provide improved fastening means whereby the attachment may be secured to various kinds 15 of containers; to provide an improved construction and arrangement of a receptacle support and drip basin adapted to fit into the filling opening of said attachment to 20 support a receptacle while being filled, and to receive any of the liquid that may be spilled or overflow the receptacle during the filling thereof; to provide improved means for draining the drip basin into the container; 25 to provide an improved construction and arrangement of the dispensing conduit and of means for permitting the attachment of gauges for measuring the liquid and the air pressure within the container; to provide improved means on the inner end 30 of said dispensing conduit adapted to accommodate said attachment to containers of varying depth; and to provide an attachment of this kind in the form of a simple and comparatively inexpensive unitary structure which can be quickly fastened to, 35 or removed from, any form of liquid container.

An illustrative embodiment of this invention is shown in the accompanying drawings in which:—

Figure 1 is a plan of a combined filling and dispensing attachment constructed in accordance with this invention.

Figure 2 is a vertical sectional elevation of the same taken on the line 2—2 of Figure 1.

Figure 3 is a detail view of a split ring

which is used in securing the attachment to certain kinds of receptacles. 50

Figure 4 is a reduced detail view of the inner end of the dispensing conduit.

Figure 5 is a fragmentary detail showing the means provided for attaching the air and liquid gauges. 55

A filling and dispensing attachment embodying this invention comprises a casing constructed for use as a sort of funnel, so that upon its being attached to a container, it may be used as a means of refilling the 60 container, and also by virtue of the dispensing conduit arranged thereon, the attachment serves to permit the dispensing of liquid from the container under air pressure. The attachment is equipped with 65 means which permit suitable gauges to be secured thereto for measuring the air pressure and liquid within the container to which the attachment is secured.

In the specific embodiment herein shown, 70 the attachment comprises a casing 1, which in the top forward portion has a filling opening 2, and in the rear bottom portion an outlet 3, the axis of which is disposed in the same vertical plane with the axis of the 75 filling opening 2, so that said outlet is located directly rearwardly of said filling opening. In its vertical cross section the casing is shaped somewhat like the mouth of a pitcher or other pouring device, whereas its horizontal cross section is of nearly 80 oval form. To permit the fastening of the attachment to containers of various kinds, the rear bottom portion thereof has integrally formed thereon a nut 4, a flange 5, and a threaded nipple 6, all of which are 85 concentrically arranged with respect to the axis of the outlet 3 and arranged one below the other. The nut 4 and threaded nipple 6 90 coact to permit the attachment to be secured to a container which is already provided with a threaded opening for that purpose, the flange 5 coacting with a split ring 7, (see Fig. 3), to permit the fastening of the attachment to a container of thin sheet metal 95 construction, and which is not equipped with

a threaded opening. The flange 5 and ring 7 are provided with holes 8 and 9, respectively, through which suitable bolts may be inserted.

5 A drip basin 10 in the form of a cup is set into the filling opening 2, the upper part of said basin and casing surrounding said opening 2, having coacting threads 11, by means of which said drip basin 10 may be screwed 10 into the casing to provide an air-tight fit. Receptacle support in the form of a spider 12 is set into the top of the drip basin 10, the periphery of the spider and the basin being provided with interfitting shoulders 15 13, (see Fig. 1), which secure the spider support against shifting in the basin. A drain 14 is formed in the rear bottom part of the basin 10 and closed by a plug 15 carried by a stem 16 extending out through the 20 top of the basin above the receptacle support 12. This stem has threaded engagement with the basin, as indicated at 17, and is provided with a winged nut head 18, so that by turning the stem 16 the plug 15 can 25 be removed from or replaced in the drain 14 without removing the receptacle support 12. The plug 15 is provided with a gasket 19, which affords an air tight closure for the drain 14 when the stem portion 17 is 30 screwed "home". Slugs 20 are formed on the top of the basin 10 at diametrically opposite points, so as to be engaged either by a spanner wrench or a rod placed across the basin between said lugs to permit the basin 35 to be turned either for screwing it firmly into place at the filling opening 2 or removing it therefrom.

40 A dispensing conduit 21 is secured to the casing 1 at the rear thereof eccentrically of the outlet 3, but with the axis thereof disposed in the same vertical plane with the axis of said outlet 3. The upper end of this conduit terminates into a faucet 22 the discharging end 23 of which is located above the filling opening 2 substantially concentric therewith. The lower end of the conduit is provided with a telescoping strainer attachment 24 (see Fig. 4), which permits the dispensing conduit 21 to be accommodated to containers of varying depths. A 45 suitable stuffing box 25 makes an air-tight connection between the conduit 21 and the extension 24.

50 Inasmuch as this attachment is intended particularly for use where the liquid is to be discharged by means of air pressure, a valve-controlled air inlet 26 is secured to the top of the casing 1 between the conduit 21 and the filling opening 2. This inlet is preferably of the conventional form of air control inlet used on pneumatic tires. It is provided with a relief outlet 27 located inwardly thereof and controlled by a pet cock 28, which when necessary, permits of a 55 quick partial or complete reduction of the

pressure within the container. A pipe 29 depends from the valve-controlled air inlet 26, the lower end thereof terminating below the casing outlet 3 (see Fig. 2).

5 In order to permit the attachment of air 70 and liquid gauges 31 and 32, respectively, (see Fig. 1), the top of the casing at opposite sides of the air pressure inlet 26 is provided with threaded nipples 33, (see Fig. 5), to which these gauges may be readily attached. These gauges may be of any of the usual constructions used for this purpose.

60 The attachment herein shown and described is used in substantially the following manner:—

As already explained, the attachment is secured to a liquid container either by screwing the threaded nipple 6 into a threaded opening in the container, or by bolting the attachment to the container by the use of 85 bolts extending through holes 8 in the flange 5, and engaging similar holes 9 in the split ring 7, which is previously inserted into the container through the opening. By means of a suitable air pump attached to the valve 90 26, a desirable amount of pressure is built up in the container. When the liquid is to be dispensed the receptacle is placed upon the spider 12 and the faucet 22 opened to permit the flow of liquid into said receptacle 95 in the desired quantity. Any liquid that may be split during the filling of the receptacle, or that may drip from the faucet is caught by the drip basin 10. When a substantial amount of liquid is accumulated in 100 the drip basin 10, the plug 15 may be withdrawn so as to permit such liquid to drain back into the container. Before opening the plug 15, the pet cock 28 is opened to dissipate the air pressure which is resupplied through inlet 26 when the plug is again 105 placed in the drain 14.

110 This attachment may be used for refilling the container by simply removing the drip basin 10, which allows the liquid to be 115 poured in through the opening 2 and flow through the outlet 3 into the container. When this is done, it is advisable to open the pet cock 28, which permits the air in the container to escape without in any way 115 retarding the flow of the liquid into the container.

120 Although but one specific embodiment of this invention has been herein shown and described, it will be understood that numerous details of the construction shown may be altered or omitted without departing from the spirit of this invention as defined by the following claims.

125 I claim:

1. A combined filling and dispensing attachment of the class described in the form of a unitary structure, comprising a casing having a filling opening in the top forward part and having an outlet at the bottom 130

rear part, means contiguous to said outlet for securing the attachment to a liquid container, a drip basin removably secured in said opening, an air-tight joint between said drip basin and said filling opening, a receptacle support arranged on said drip basin, a dispensing conduit secured at the rear of said casing and terminating at its upper end in a faucet disposed above said filling opening, and a valve-controlled air inlet through which air under pressure may be admitted to the container.

2. A combined filling and dispensing attachment of the class described in the form of a unitary structure, comprising a casing having a filling opening in the top forward part and having an outlet at the bottom rear part, means contiguous to said outlet for securing the attachment to a liquid container, a drip basin removably secured in said opening with an air-tight joint, said drip basin having a drain in the rear bottom part thereof and having the bottom of said basin inclined toward said drain, a receptacle support arranged on said drip basin, a dispensing conduit secured at the rear of said casing and terminating at its upper end in a faucet disposed above said filling opening, a plug for said drip basin drain, a stem on said plug extending above said receptacle support to permit the removal and replacement of said plug without disturbing said support, and a valve-controlled air inlet through which air under pressure may be admitted to the container.

3. A combined filling and dispensing attachment of the class described in the form of a unitary structure, comprising a casing having a filling opening in the top forward part and having an outlet at the bottom rear part, means contiguous to said outlet for securing the attachment to a liquid container, a drip basin, coacting threads on the upper periphery of said basin and on the casing around said opening whereby said basin is screwed into said opening an air-tight joint between said drip basin and said filling opening, a receptacle in the form of a spider seated on the top of said basin, interfitting shoulders on said spider and basin adapted to secure said spider in place, a dispensing conduit secured at the rear of said casing and terminating at its upper end in a faucet disposed above said filling opening, and a valve-controlled air inlet through which air under pressure may be admitted to the container.

4. A combined filling and dispensing attachment of the class described in the form of a unitary structure, comprising a casing having a filling opening in the top forward part and having an outlet at the bottom rear part, a drip basin removably secured in said opening, an air-tight joint be-

tween said drip basin and said filling opening a receptacle support arranged on said drip basin, a dispensing conduit secured at the rear of said casing and terminating at its upper end in a faucet disposed above said filling opening, a valve-controlled air inlet through which air under pressure may be admitted to the container, a flange formed on the bottom rear part of said casing concentric with said outlet and having a plurality of bolt holes therein, and a threaded nipple formed on said casing below and concentric with said flange, said flange and nipple enabling said attachment to be threaded or bolted to the liquid container.

5. A combined filling and dispensing attachment of the class described in the form of a unitary structure, comprising a casing having a filling opening in the top forward part and having an outlet at the bottom rear part, means contiguous to said outlet for securing the attachment to a liquid container, a drip basin removably secured in said opening, an air-tight joint between said drip basin and said filling opening a receptacle support arranged on said drip basin, a dispensing conduit secured at the rear of said casing and terminating at its upper end in a faucet disposed above said filling opening, a valve-controlled air inlet through which air under pressure may be admitted to the container, said casing having nipples thereon for attachments of air and oil gages.

6. A combined filling and dispensing attachment of the class described in the form of a unitary structure, comprising a casing having a filling opening in the top forward part and having an outlet at the bottom rear part, with the axis thereof in the same vertical plane with the axis of said filling opening, means contiguous to said outlet for securing the attachment to a liquid container, a drip basin removably secured in said opening, an air-tight joint between said drip basin and said opening, a receptacle support arranged on said drip basin, a dispensing conduit secured at the rear of said casing contiguous to said outlet and having the axis thereof located in the same plane as the axis of said outlet, said dispensing conduit terminating at its upper end in a faucet disposed above said filling opening, a valve-controlled air-pressure inlet arranged on the top of said casing between said filling opening and said dispensing conduit, and means on the top of said casing at each side of said air pressure inlet adapted to have liquid and air pressure gauges respectively attached thereto.

7. A combined filling and dispensing attachment of the class described in the form of a unitary structure, comprising a casing having a filling opening in the top forward part and having an outlet at the bottom rear part, means contiguous to said outlet for se-

curing the attachment to a liquid container, a drip basin removably secured in said opening, an air-tight joint between said drip basin and said opening, a receptacle support ¹⁰ arranged on said drip basin, a dispensing conduit secured at the rear of said casing and terminating at its upper end in a faucet disposed above said filling opening, a valve-

controlled air inlet through which air under pressure may be admitted to the container, and a pipe depending from said inlet and terminating below said casing outlet.

Signed at Chicago this 30th day of October 1922.

ALEX E. LOOKHOLDER,
